FIG. 2

Patented May 15, 1928.

1,670,142

UNITED STATES PATENT OFFICE.

DANIEL DEE, OF MINNEAPOLIS, MINNESOTA, ASSIGNOR OF ONE-HALF TO CHARLES E. OVENSHIRE, OF MINNEAPOLIS, MINNESOTA.

ANTI-GLARE DEVICE FOR HEADLIGHTS.

Application filed June 4, 1926. Serial No. 113,730.

This invention relates to an improved anti-glare device adapted for use in connection with automobile headlights to prevent them from casting a glare ahead of the vehicle and interfering with the vision of approaching motorists or pedestrians, and is designed as an improvement of the invention set forth in the joint application of Daniel Dee and Charles R. Carpenter Serial Number 689,258, filed Jan. 29, 1924.

An object of the invention is to provide an anti-glare device of simple and inexpensive construction, which may readily and quickly be attached to the usual reflector of a headlight in a minimum of time, and independently of the light bulb thereof.

A further object of the invention is to provide such a device of flexible sheet material, which may be either opaque or translucent, comprising preferably three sections, one of which is adapted to be positioned in front of the light bulb to obscure the filament thereof to prevent glaring of the headlight, and another section having a suction means provided thereon and engageable with the surface of the reflector, to hold the device thereon independently of the light bulb.

Other objects of the invention will appear from the following description and the accompanying drawings and will be pointed out in the annexed claims.

In the accompanying drawings there has been disclosed a structure designed to carry out the various objects of the invention, but it is to be understood that the invention is not confined to the exact features shown, as various changes may be made within the scope of the claims which follow:

In the accompanying drawings:

Figure 1 is a vertical sectional view of an ordinary form of automobile headlight showing the invention applied thereto;

Figure 2 is a front view of Figure 1;

Figure 3 is a perspective view of the improved device removed from the headlight; and

Figure 4 illustrates a modified construction wherein the anti-glare device is secured to the reflector above the light bulb.

In the selective embodiment of the invention here shown, for purposes of disclosure, there is illustrated an automobile headlight, comprising the usual casing 4, reflector 5 and lens 6 secured to the casing by means of the usual retaining ring 7. The usual

light bulb 8 is shown mounted in the bayonet socket 9 secured to the casing 4 in the usual manner.

The novel anti-glare device featured in this invention comprises a front section 10, a top section 11 and a rear section 12, formed of sheet material, preferably translucent, such as celluloid, or it may be opaque if desired.

A key slot 13 is provided in the depending rear section 12 adapted to receive a suction cup 14 of ordinary construction, having a flanged head 15 thereon received in the lower reduced portion of the slot 13, as shown in Figures 1 and 3. The upper enlarged portion of the slot 13 is adapted to be traversed by the plug 16 of the light bulb 8, when the device is mounted upon the reflector, as shown in Figure 1.

The top section 11 is preferably horizontally disposed over the light bulb, as shown in Figures 1 and 3, and the front section 10 extends downwardly and forwardly therefrom to a position in front of the light bulb, to obscure the filament thereof to prevent glaring of the headlight. The rear section 12 depends from the top section 11, preferably at right angles thereto, and preferably is straight as shown in Figure 3, before mounting in the headlight. When the device is mounted upon the reflector within the headlight the lower portion of the rear section 12 may be bent, as shown in Figure 1, in order to properly position the device over the light bulb, as shown in this figure.

By means of the suction cup 14 the device may quickly be attached to any ordinary reflector without the use of tools, by simply removing the lens 6 from the headlight and then removing the light bulb from its socket. The device may then be mounted upon the surface of the reflector and the plug 16 of the light bulb inserted through the enlarged portion of the key slot 13 and into its socket, thereby rendering a glaring headlight non-glaring. Thus by the employment of this simple device, a headlight provided with an ordinary reflector and a plain lens may quickly be rendered non-glaring.

Figure 4 illustrates a modified construction wherein the device consists of a plate 17, of similar material, having an offset portion 18 apertured to receive the suction cup 14, in a manner similar to that shown and described with reference to the previous figures. The device shown in Figure 4 may be

secured to the surface of the reflector without removing the light bulb from its socket.

I claim as my invention:

1. The combination with a headlight reflector having a light bulb therein, of a flexible anti-glare device comprising front, top and rear sections, formed of translucent sheet material, the top section being horizontally disposed above said light bulb in close proximity thereto, and the front section diverging downwardly to a position in front of said bulb and also in close proximity thereto, and the rear section depending from said top section and having an aperture therein traversed by the plug of said bulb, and a suction cup demountably and terminally secured to said rear section and arranged for engagement with the surface of said reflector, whereby said anti-glare device may be demountably attached to the surface of said reflector.
2. In combination with a reflector having a lamp socket and light bulb including a plug detachably engaged in said socket, a strip of opaque material secured to the reflector and arranged over the bulb to engage the same substantially at the front side, said strip having an opening loosely traversed by the plug and further having a slot in said opening to form therewith a key hole slot, and a vacuum cup detachably secured within the slot, and engaged with the reflector to secure the strip in operative position, said

slot and cup lying below the bulb when the device is in operative position.

35

3. In combination with a reflector having a light bulb, a flat strip of material secured to the reflector and arranged to screen the bulb at the top and outer end only.

40

4. In combination with a headlight reflector having a light bulb, a flat strip of material arranged to screen the bulb at the top and outer end only, said strip being adjustably removably secured to the reflector.

45

5. In combination with a headlight reflector having a light bulb, a flat strip of material arranged to screen the bulb at the top and outer end only, said strip being secured to the reflector, and said strip being of a width substantially equal to the diameter of the bulb.

50

6. In combination with a reflector having a light bulb including a plug detachably secured in the socket, a strip of material secured to the reflector and arranged to screen the bulb at the top and outer end only, said strip having an opening traversed by the plug and further having a slot extending from said opening to form therewith a key-hole slot, and a vacuum cup detachably secured within the slot and engaged with the reflector to secure the strip in operative position.

55

In witness whereof, I have hereunto set my hand this 28th day of May, 1926.

DANIEL DEE.
